The ornamental design for a multi-compartment detergent unit dose, as shown and described.

DESCRIPTION

FIG. 1 is a top perspective view of a first embodiment of a multi-compartment detergent unit dose showing our new design;

FIG. 2 is a top view of the design of FIG. 1;

FIG. 3 is a bottom view thereof of FIG. 1;

FIG. 4 is a front view thereof of FIG. 1;

FIG. 5 is a rear view thereof of FIG. 1;

FIG. 6 is a right side view thereof of FIG. 1; and

FIG. 7 is a left side view thereof of FIG. 1.

FIG. 8 is a top perspective view of a second embodiment of a multi-compartment detergent unit dose showing our new design;

FIG. 9 is a top view of the design of FIG. 8;

FIG. 10 is a bottom view thereof of FIG. 8;

FIG. 11 is a front view thereof of FIG. 8;

FIG. 12 is a rear view thereof of FIG. 8;

FIG. 13 is a right side view thereof of FIG. 8; and,

FIG. 14 is a left side view thereof of FIG. 8.

FIG. 15 is a top perspective view of a third embodiment of a multi-compartment detergent unit dose showing our new design;

FIG. 16 is a top view of the design of FIG. 15;

FIG. 17 is a bottom view thereof of FIG. 15;

FIG. 18 is a front view thereof of FIG. 15;

FIG. 19 is a rear view thereof of FIG. 15;
